TOILET ARTICLE

George H. Hutaft, Jr., Wilmington, N. C.

Application February 28, 1944, Serial No. 524,262

5 Claims. (Cl. 132—75.6)

This invention relates to improvements in toilet articles and more particularly to a combination implement involving a comb and devices carried thereby, such as a nail file and knife blade, secured together and correlated to be confined within an area of but slightly greater than that customarily defined by a pocket comb.

A preferred embodiment of the invention comprises the comb having end formations for nesting flat or blade-like implements (files or knives) to be normally confined in closed or nested relationship in the end portions of the comb, but capable of convenient opening with reference to the body of the comb to maintain the same in operative position under the utilization of the body of the comb as a handle.

Details of construction, in the association or mountings of the various implements of the combined device, may be resorted to as may be embraced within the terms of the hereto appended claims. Among these may be mentioned two other embodiments of the invention comprising, on the one hand, the provision of means formed separately from the comb and attached to the back and ends thereof to constitute the receiving and protecting housings for the file or blade attachments; and, on the other hand, the frame for the end receiving and protecting housings aforesaid, elongated and carried throughout the length of the back of the comb, and secured thereto, to tie the end members together in further reinforcing and strengthening the same as well as the comb structure.

All of the embodiments of the invention recited are illustrated in the accompanying drawings forming a part hereof and they will be further defined hereinafter.

In the drawings:

Figure 1 is a face view of the combined implement first referred to, the open state of the blade-like implements being indicated in dotted lines,

Fig. 2 is an end view,

Fig. 3 is an enlarged section of one end of the implement, and

Fig. 4 is a top edge view of one end of the implement.

Fig. 5 is a face view of the second-mentioned embodiment of the invention,

Fig. 6 is an end view of the same, and

Fig. 7 is an enlarged view of one end of the implement of Fig. 5, parts being broken away.

Fig. 8 is a face view of the third mentioned embodiment of the invention,

Fig. 9 is an end view of the same,

Fig. 10 is a view similar to Fig. 7, and

Fig. 11 is a transverse section through the back of the comb, the comb being of the same general configuration throughout the various embodiments of the invention.

Referring more specifically to the drawings wherein like reference characters designate the same parts in the respective series of views, 1 designates the back of a comb having an enlarged oval cross-section to give the same strength and reinforcement, 2 the teeth secured integrally with the back, as usual, and projecting therefrom, and 3 the end members of the comb or end teeth of an enlarged or rigid character, constituting with the back 1, the frame of the comb.

In the form of the invention illustrated in the first series of views these end members 3 of the frame of the comb are provided with slots 4 passing from the outer ends of the comb 20 through the inner sides of the end frame members 3 to provide ways 5 in which comparatively thin blade members 6, as a nail file, and 7 as a manicuring blade or the like, may be confined. These slots or ways are carried upwardly through 25 the back 1 of the comb and terminate in short grooved portions 8, in the end portions of said back, said grooved portions being of shallow depth terminating in shoulders or stops 9 for a purpose as will appear.

30 The blade-like portions, to wit: The file 10 and knife blade 11, are pivoted in the grooved portions of the comb, and normally confined therein, pins or rivets 12 passing through the opposite portions of the back 1 and the slotted 35 portions of the same, and the upper ends of the blade portions having a pivotal movement on or through the medium of the pins or rivets. The parts being so closely fitted, in other words in a binding relationship, to frictionally hold the file or knife, as the case may be, either in closed 40 position for nesting or open position for operation. In the latter position, shoulders or stops 13, at the ends of the blades beyond the pivoting thereof will contact the cooperative shoulders or stops 9 in the grooved portions at the 45 back of the comb to prevent further opening movement of the blades and thus retain the same in reinforced position for use in filing or cutting under manipulation of the body of the comb as a handle.

When the bladed portions are closed into nested or housed position relative to the ends of the comb, the inner edges of the blades contact the flexible and yieldable end tooth of the comb, the latter serving to prevent excessive closing

of the blade. The end teeth, referred to, flexing a little under the pressure of the closing blade, will not impair the sharp or cutting edge thereof.

The specific description thus far given will appropriately describe generally features of the embodiments of the invention illustrated in the two additional sets of views. It, however, remains to point definitely to some characteristic differentiating features thereof.

On the one hand, the form of Fig. 5 etc. comprises a pair of housing or protecting shields or plates 14, adapted to receive therebetween the ends of the comb, and having inward extensions 15 adapted to be riveted as at 16 in fixed position to the back 17 of the comb and similarly riveted as at 18 to the end members or teeth of the comb. The blade-like members (file and knife) are pivoted to the plates 14 as at 20 and work therebetween to open and close with reference thereto, the end of each blade member having a shoulder 21 to engage a complementary stop shoulder 22 in a short-slotted portion 23, at the corresponding end of the back of the comb.

On the other hand, and relative particularly to the form illustrated in the remaining views, Fig. 8, etc., the plates 24 are connected together by a continuous back piece 25 of somewhat springy character, it being understood that all of the parts throughout, other than the comb itself, are formed preferably of metal, conforming to the cross section of the back of the comb to closely hug said back and tie the plates 24 integrally together, thus reinforcing the structure. The metal connecting member 25 is preferably also riveted as at 26, through the back of the comb.

In the two embodiments of the invention last discussed it will be understood that the blades (nail file and knife) when housed, abut at their inner edges with the surfaces of the end teeth (Fig. 10) or the riveted frame members of the comb (Fig. 7) to prevent a too-far swinging of the blades inwardly of the comb structure.

I claim:

1. An implement of the character described comprising a frame having an elongated relatively horizontally disposed member adapted to constitute an operating handle, and a relatively vertically disposed sheath offset in a downward direction therefrom and open at its outer edge, in combination with a pivoted implement mounted to swing into and out of said edge opening of the sheath whereby said implement may be protected by the latter when swung downwardly and inwardly relative to the handle and will occupy an operative position when swung outwardly and upwardly in approximate alignment with the handle and extended from the end thereof, the opening in the sheath passing entirely therethrough, and a yieldable member opposite the rear end of said opening constituting an abutment to be engaged by the corresponding edge of the implement when closed.

2. An implement of the character described comprising a frame having an elongated relatively horizontally disposed member adapted to constitute an operating handle, and a relatively vertically disposed sheath offset in a downward direction therefrom and open at its outer edge,

in combination with a pivoted implement mounted to swing into and out of said edge opening of the sheath whereby said implement may be protected by the latter when swung downwardly and inwardly relative to the handle and will occupy an operative position when swung outwardly and upwardly in approximate alignment with the handle and extended from the end thereof, the sheath being a separate member relative to the handle having an upper portion overlying and fastened to the latter and the implement-receiving portion thereof depending therefrom, the opening in the sheath passing entirely therethrough, and a yieldable member opposite the rear end of said opening constituting an abutment to be engaged by the corresponding edge of the implement when closed.

3. An implement of the character described comprising a frame having an elongated relatively horizontally disposed member adapted to constitute an operating handle, and a relatively vertically disposed sheath offset in a downward direction therefrom and open at its outer edge, in combination with a pivoted implement mounted to swing into and out of said edge opening of the sheath whereby said implement may be protected by the latter when swung downwardly and inwardly relative to the handle and will occupy an operative position when swung outwardly and upwardly in approximate alignment with the handle and extended from the end thereof, the sheath being a separate member relative to the handle having an upper portion overlying and fastened to the latter and the implement-receiving portion thereof depending therefrom, the upper portion of the sheath being co-extensive with the handle and embracing the latter from end-to-end thereof and terminating in a second sheath portion offset from the other end of the handle adapted to accommodate another implement.

4. An implement of the character described comprising a frame having an elongated member adapted to constitute an operating handle and offset end portions depending therefrom, implement supporting means comprising a portion approximately U-shape in cross-section and co-extensive with said elongated member open along its inner edge to embrace the same, securing means therefor, sheathing portions at the opposite ends of said implement supporting means and offset therefrom to overlie the corresponding offset portions of said frame member and project outwardly therefrom, and implements mounted to move into and out of said sheathing portions, substantially as described.

5. An implement of the character described comprising a frame having an elongated member adapted to constitute an operating handle and an offset end portion depending therefrom, implement supporting means comprising portions adapted to overlie the sides of said elongated member and depending portion, means for securing the implement supporting means in place, a sheathing portion projecting outwardly from the depending portion of the elongated member, and an implement mounted for movement into and out of said sheathing portion, substantially as described.

GEORGE H. HUTAFF, JR.
